UNITED STATES PATENT OFFICE

168,094

COMBINED BANK AND ASH TRAY

Clarence E. Holmes, Tallahassee, Fla.

Application May 13, 1952, Serial No. 19,691

Term of patent 7 years

(Cl. D34—11)

To all whom it may concern:

Be it known, that I, Clarence E. Holmes, a citizen of the United States, residing at Tallahassee, in the county of Leon and State of Florida, have invented a new, original, and ornamental Design for a Combined Bank and Ash Tray, of which the following is a specification, reference being had to the accompanying drawing, forming a part thereof.

Figure 1 is a side elevational view of a combined bank and ash tray, showing my new design;

Figure 2 is a top plan view; and

Figure 3 is a rear elevational view.

I claim:

The ornamental design for a combined bank and ash tray, as shown.

CLARENCE E. HOLMES.
